(No Model.)

J. S. HAUSMAN.

BALL RACK FOR POOL PLAYING.

No. 293,458.

Fig. 1

Patented Feb. 12, 1884.

UNITED STATES PATENT OFFICE.

JACOB S. HAUSMAN, OF NEW YORK, N. Y.

BALL-RACK FOR POOL-PLAYING.

SPECIFICATION forming part of Letters Patent No. 293,458, dated February 12, 1884.

Application filed December 31, 1883. (No model.)

To all whom it may concern:

Be it known that I, JACOB S. HAUSMAN, of the city, county, and State of New York, have invented a new and useful Improvement in 5 Ball-Racks for Pool-Playing, of which the following is a full, clear, and exact description.

Reference is to be had to the accompanying drawings, forming a part of this specification, in which similar letters of reference indicate 10 corresponding parts in all the figures.

Figure 1 is a front elevation of my improvement, partly in section. Fig. 2 is a sectional side elevation of the lower part of the same, taken through the line $x-x$, Fig. 1. Fig. 3 is 15 the same section as Fig. 2, but showing the hinged plate and its attachments raised into a horizontal position. Fig. 4 is a cross-section of the lower part of the hinged plate and its attachments, taken through the line $y-y$, Fig. 1.

20 The object of this invention is to facilitate the removal of the balls used in pool-playing from the racks and the placing of the said balls upon the tables.

The invention consists in a ball-rack constructed with a back plate having vertical rack-bars and having plates hinged to the lower edge of the said back plate and the lower ends of the rack-bars, the said hinged plates being connected by pivoted bars and levers, so that the 25 upward movement of the lower plate will swing the upper plate downward. To the lower hinged plate are attached dovetailed flanges to receive and hold a triangular plate, which is also provided with dovetailed flanges to receive and hold the triangle to receive the balls. 30 To the downward extension of the back plate are secured short spouts to guide the balls from the side parts of the rack to the triangle, as 35 will be hereinafter fully described.

40 A is the back plate of the rack, to the forward side of which are attached upright bars B, at such a distance apart as to readily receive the balls between them, as shown in dotted lines in Fig. 1. The bars B are made 45 with concaved sides, and have narrow cap-plates C attached to their forward edges, which cap-plates may have their side edges scalloped to allow the balls to be readily inserted between the said bars B.

50 To the tops of the bars B is attached a

cornice, D, which may be ornamented to any desired extent.

To the lower ends of the bars B is hinged a plate, E, in such a manner that it can be swung into a horizontal position beneath the lower ends of the said bars B to support the balls when in the rack, as shown in Fig. 2, and swung back, as shown in Fig. 3, to allow the said balls to pass out of the said rack.

To the inner corners of the hinged plate E 60 are pivoted the ends of short bars F, the other ends of which are pivoted to the inner ends of short bars or levers G, pivoted at their middle parts to the side bars, B.

To the outer ends of the levers G are pivoted 65 the upper ends of the curved bars H, the lower ends of which are pivoted to the ends of the plate I at a little distance from their upper corners. The upper edge of the plate I is hinged to the lower edge of the back plate, A, 70 in such a manner that the said plate I can be swung forward into a horizontal position, as shown in Fig. 3. The middle part of the plate I is extended downward in the form of a truncated triangle, as shown in Fig. 1, and to the inclined side edges of the said extension of the said plate are attached flanges J, the upper ends of which are extended upward nearly to the upper edge of the said plate I. The inner sides of the flanges J are dovetailed to fit upon the 75 side edges of the triangular plate K, which has flanges L attached to its side edges. The inner sides of the flanges L are dovetailed to receive the dovetailed edges of the triangle M. The third side or base of the triangular plate 80 K is made without a flange, so that the triangle M can be readily slipped on and off the said plate. With this construction the triangular plate K and the triangle M will retain their places upon the hinged plate I when the said plate I is hanging in a vertical position, as 85 shown in Figs. 1 and 2.

The back plate, A, extends downward below the lower ends of the rack-bars B a sufficient distance to allow the balls to pass from the 90 spaces between the said rack-bars, beneath the lower edge of the hinged plate E, into the triangle M when the hinged plate I has been raised into a horizontal position. To the end parts of the downward extension of the back 95 plate A are secured short spouts, which serve to 100 guide the balls from the side parts of the rack to the triangle M.

plate, A, are attached short spouts N, to guide the balls from the side spaces of the rack into the triangle M. With this construction, when the balls are placed in the rack, they are supported by the hinged plate E, upon which the lowest balls rest, as shown in dotted lines in Fig. 1 and in full lines in Fig. 2.

When the balls are to be removed from the rack, the hinged plate I is raised into a horizontal position, which swings the hinged plate E downward and allows the balls to roll out of the spaces between the bars B into the triangle M. The triangular plate K and the triangle M are then slipped back a little to free the dovetailed edges of the plate K from the dovetailed flanges J, and the plate K, the triangle M, and the balls are removed together from the plate I and are placed upon the table. The plate K is then slipped out from beneath the triangle M and the balls, and the triangle M is lifted from the table, leaving the balls upon the table in proper position to be used.

Having thus described my invention, I claim as new and desire to secure by Letters Patent—

1. A ball-rack constructed substantially as herein shown and described, and consisting of the back plate having a plate hinged to its

lower edge and provided with vertical rack-bars having a plate hinged to their lower ends, the two hinged plates being connected by pivoted bars, and levers so arranged that the upward movement of the lower plate will swing the upper plate downward, as set forth. 30

2. In a ball-rack, the combination, with the back plate, A, and the rack-bars B, of the hinged plates E I, the pivoted connecting bars and levers F H G, the triangular plate K, and the triangle M, substantially as herein shown and described, whereby the balls will be made to pass from the rack to the triangle automatically, as set forth. 35

3. In a ball-rack, the combination, with the hinged plate I, having dovetailed flanges J, of the triangular plate K, having dovetailed flanges L, and the triangle M, having dovetailed sides, substantially as herein shown and described, whereby the said triangular plate and triangle will be kept in place when the hinged plate hangs in a vertical position, as set forth. 40 45

JACOB S. HAUSMAN.
